Attorney

UNITED STATES PATENT OFFICE

GIUSEPPE RIGANTE, OF WESTERLEIGH, STATEN ISLAND, NEW YORK

COIL UNIT

Application filed April 22, 1931. Serial No. 532,040.

The present invention relates to new and useful improvements in electrical devices, and more particularly it pertains to a coil unit which although of broad application, is particularly adapted for use in radio work.

It is one of the objects of the present invention to provide a coil unit in which a plurality of coils may be carried in a single unit.

It is a further object of the invention to construct a device of the aforementioned character in such a manner that although the several coils are enclosed and shielded, access to the coils may be readily had without damage to the enclosures thereof.

It is a further object of the invention to provide a device of the aforementioned character in which any number of coils may be employed and so arranged upon a common support that interference between the coils will be eliminated.

With the above and other objects in view, reference is had to the accompanying drawing, wherein,

Figure 1 is a perspective view of a coil unit constructed in accordance with the present invention,

Figure 2 is a longitudinal sectional view of a coil unit constructed in accordance with the present invention,

Figure 3 is a horizontal sectional view taken on the line 3—3 of Figure 2; and

Figure 4 is a detail perspective view of one of the elements of the coil supporting member.

A coil unit constructed in accordance with the present invention, consists of a base 5 which is preferably circular in form, and is formed from any suitable non-conducting material such as hard rubber or the like. The base 5 has a plurality of slots 6 formed therein and said slots intersect each other in the manner of a cross.

Retained in the slots 6 of the base 5, there is a coil supporting member 7 and said coil supporting member is cross shape in cross sectional form, and is of different diameters and various points throughout its length, that is to say, the elements which form the coil supporting member 7 are reduced in width in the direction of one of their ends.

The coil supporting member 7 comprises two members 8. Each of these members 8 is provided with a centrally disposed longitudinally extending slot 9 which extends throughout approximately half of the length 65 of the member and from the base of said slot to the opposite end of the members 8, said members are provided with grooves or the like 10. This construction permits the two members 8 to be arranged in substantially 60 right angular plane and connected together by interlocking of the members, the grooved portion of each member being received in the slotted portion of the opposite member as indicated at 12 in Figure 3. Thus it will 65 be apparent that when the members are placed together as described, a coil supporting member 7 of cross shape in cross sectional form will be provided, and that the members 8 are so arranged and constructed 70 that their corresponding reduced portions will coincide in order to provide winding spaces for the coils.

One end of the coil supporting member 7 is inserted in the cross shaped slots heretofore mentioned in the base 5, and the coil supporting member 7 stands in an upright position with relation to said base 5.

Means is provided to inclose the major portion of the coil supporting member 7, and 80 to form a shield for the several coils carried thereby. In the present embodiment of this invention, the shielding means consists of a plurality of cylindrical members 15, 16 and 17 of various diameters, the member 15 being larger in diameter than the member 16 and the member 17 being smaller in diameter than the member 16 forms the intermediate shield member. The shield member 15 may be secured to the base 5 in any desired manner and is of a length that its upper end will be flush with the shoulder formed by the intermediate reduced portion of the members 8. Resting upon the upper end of the shield member 15 and secured thereto by 95 suitable clips 18, there is a ring like member 19 and this ring like member 19 forms the support for the second shield member 20. This shield member 20 is of such length that its upper end is flush with the shoulder 100

formed by the end reduced portion of the members 8, and supported on said shoulder there is a ring like member 21 which is secured thereto by means of clips 22 and supported upon the ring like member 21 there is a third shield member 23 which has its free end partially closed by means of a ring like member 24 secured thereto by means of clips 25. It will be noted that the several 10 clips 18, 21 and 25 are in the form of right angular members and are secured to their respective shield members by means of screws or the like 27 threaded into openings in the shield members. The several shield members 15 are provided with openings 30 through which the leads from the coils carried thereby may extend and as best illustrated in Figure 4, the members 8 which form the coil support are provided with openings 27' 20 through which these leads of the coils pass and by means of which they may be secured to the coil support 7 before passing through the openings 30 of the shield members.

It is to be understood that the members 8, 25 shields 15, 16 and 17, and the rings 19, 20 and 24, are formed from any suitable non-conducting material preferably of the same type and character as that employed in the manufacture of the base 5.

30 From the foregoing it will be apparent that the present invention provides a new and novel coil unit in which a plurality of coils of any desired capacity or character may be wound and subsequently enclosed and shielded against interference one with another.

While the invention has been herein illustrated in a preferred form, it is to be understood that the invention is not to be limited 40 to the specific construction herein shown and that it may be practiced in other forms without departing from the spirit thereof.

Having thus described the invention, what is claimed as new and what it is desired to 45 secure by Letters Patent of the United States, is:

1. A coil supporting device comprising a base member, a coil supporting member removably carried thereby and projecting from 50 the base member, a plurality of coils formed on said coil supporting member, and shielding means supported from the base and surrounding said coil supporting member, said shielding means comprising a plurality of 55 separate sections of insulating material separating certain of the coils on the coil supporting member, and means for removably securing said sections together to form the shield.

60 2. A coil unit of the type described comprising a base member, two relatively long narrow members each provided with a slot extending lengthwise thereof throughout substantially half of the length thereof, 65 whereby said members may be arranged to-

gether in interlocking right angular relation, means for securing said members to the base, and shielding means carried by the base and adapted to enclose said coil supporting member, said shielding means comprising a plurality of sections of different diameters, and means for detachably connecting said sections together.

3. A coil support and housing member comprising a base, a coil supporting member 75 removably carried by said base, and adapted to support a plurality of coils, and means for enclosing said coil supporting member and comprising a plurality of cylindrical members removably engaging said coil supporting member and means for removably securing said cylindrical sections together to form the enclosing housing.

4. A coil support and housing member comprising a base, a coil supporting member 85 extending from said base, a cylindrical member carried by said base and surrounding a portion of said coil supporting member, a ring-like member carried by the upper end of said cylindrical member and removably secured thereto and other cylindrical members enclosing the coil supported member and supported by the ring like member carried by the first mentioned cylindrical member.

5. A coil support and housing comprising 90 a base, an elongated coil supporting member extending therefrom, a plurality of cylindrical members arranged in superposed relation and enclosing said coil supporting member, supporting means interposed between 100 said cylindrical members and means for attaching said supporting means to said cylindrical members.

6. A coil support and housing comprising 105 a base, an elongated coil supporting member extending from and supported by said base, a cylindrical member supported by said base, and enclosing a portion of the coil supporting member, a second cylindrical member enclosing an intermediate portion of said 110 coil supporting member, means for supporting said second mentioned cylindrical member from the first mentioned cylindrical member, a third cylindrical member enclosing the remaining portion of the coil supporting 115 member, means for supporting said last mentioned cylindrical member from the second mentioned cylindrical member, and means for removably attaching each of said cylindrical member supporting means to its respective cylindrical member.

In testimony whereof I affix my signature.
GIUSEPPE RIGANTE.
